United States Patent Office

Des. 195,371
Patented June 4, 1963

195,371
BOTTLE

Albert Henry Torongo, Washington Crossing, Pa., assignor to The Procter & Gamble Company, Cincinnati, Ohio, a corporation of Ohio

Filed Dec. 19, 1962, Ser. No. 72,903

Term of patent 14 years

(Cl. D58—8)

Fig. 2

Fig. 1

Fig. 4

Fig. 3

FIG. 1 is a front elevational view of a bottle showing my new design.

FIG. 2 is a side elevation of the same.

FIG. 3 is a top plan view of the same.

FIG. 4 is a cross-sectional view taken on the line 4—4 of FIG. 1.

I claim:

The ornamental design for a bottle, as shown.
